INTERNAL COMBUSTION ENGINE

Alfred Büchi, Winterthur, Switzerland

Application April 21, 1927, Serial No. 185,558
In Switzerland April 30, 1926

1 Claim. (Cl. 123—140)

This invention relates to internal combustion engines particularly to those getting their charge precompressed, the precompressor being driven by an exhaust gas turbine actuated by the exhaust gases of the internal combustion engine or by the combustion engine itself. The fuel supply to an ordinary internal combustion engine is regulated in a well known manner by a governor in accordance with the load on the engine. 10 This regulation would not sufficiently protect an engine with an exhaust gas driven precompressor as will be explained hereinafter. If for instance full load is on the engine and the pressure of the charging air drops all of a sudden (break down of the precompressor, leak in the pressure piping, closing of air valves or the like), the pressure at the beginning of the compression stroke becomes lower and also the compression pressure, in other words the output of the internal combustion engine decreases. As the load is still on, the revolutions drop, the ordinary governor starts now to act in such a manner as to feed more fuel to the combustion cylinders in order to speed the engine up again. Although the air pressure has dropped, more and more fuel is fed to the cylinders which results in bad combustion, after-burning and very high temperatures, which may result in severe damage especially to cylinder head and valves. In this moment the device 20 according to this invention starts to act. The fuel supply to the combustion cylinders is checked by means described hereinafter, so that at each value of the air pressure only one fixed amount of fuel is supplied to the combustion cylinders 25 regardless of the position of the governor, whereby this amount of fuel is the higher, the higher the pressure of the precompressed air is. In other words, the ratio, weight of air divided by weight of fuel, does not drop below a certain 30 limit, allowing a safe operation of the internal combustion engine. I want to point out, that the device checking the fuel supply must not absolutely be operated by the pressure of the charging air but must also be operated by the pressure of the exhaust gas from the internal combustion engine. In the accompanying drawing constructional examples of devices for carrying out the invention are shown.

50 Figure 1 shows an arrangement of a multi-cylinder internal combustion engine according to the invention.

Figures 2, 3 and 4 show detailed modified forms of the controlling apparatus indicated at 8 and 9 in Figure 1.

Figure 5 shows a plan of the device 8 of Figure 2, but including also the eccentric 27.

In Figure 1, 1 is an internal combustion engine having the cylinders 2, 3, 4, 5, 6 and driving a generator 7. 8 is the governor of the internal combustion engine, regulating the fuel quantity supplied to the combustion cylinders by the fuel pump 9 and is of conventional form. 10 denotes the charging compressor driven by an exhaust gas turbine 11. From the internal combustion engine 1 the exhaust gases are led to the turbine 11 by the exhaust pipe 12. To by-pass the exhaust gases to the atmosphere, a pipe 13 branches off the pipe 12 and can be opened or closed to the atmosphere by means of valve 14. The compressor delivers the charging air through pipe 15, common to all cylinders, to the internal combustion engine. The engine can also draw in air directly from the atmosphere by opening valve 16, for instance when the engine is running idle or at small loads. Numeral 17 denotes an electric motor which can be switched on and drives the charging compressor whenever it is necessary. In order to limit the delivery of the fuel pump 9 to the internal combustion engine a pipe 18 leads from the charging air pipe 15 to a device described hereinafter, preventing more fuel being fed to the engine than can be admitted if the combustion temperatures are not to exceed a fixed maximum.

Figure 2 shows such a device in detail. The internal combustion engine, which is omitted for clearness' sake, is provided with a fuel pump 9, with piston 22 actuated by eccentric 20 on shaft 26. 23 is the delivery and 24 the suction valve. 25 is the fuel delivery pipe leading to the cylinders of the internal combustion engine. The fuel pump 9 is regulated by the governor 8, which shifts an eccentric 27 on the rotating shaft 26, see also Figure 5, so that the regulating member 28 allows to close suction valve 24 earlier or later. The eccentric 27 forms a sleeve connected to the weights of the governor with the links 55. According to each position of these weights fulcrumed at 53, corresponds a position of the eccentric 27. The governor 8 and eccentric 27 rotate with the cam shaft 26, the governor being keyed to said shaft. The quantity of fuel fed to the combustion cylinders is regulated by the earlier or later closing of the suction valve 24. Pipe 31 leading to the pump 9 is the suction pipe and can be closed by means of valve 32. The device according to the present invention comprises a cylinder 33 and pipe 18 connected 55

to its upper part. Pipe 18 communicates with the charging pipe 15 or may communicate with one of the pressure stages of the blower through the pipe 18' (Figure 1). In the cylinder 33 moves a piston 34 with the piston rod 35 which acts by means of levers 36 on the shaft 30. Lever 29 is eccentric on shaft 30, so that by turning the latter, the position of lever 29 can be varied. The lever 29 is acted upon by the member 28 which in turn is acted upon by a sleeve surrounding the eccentric 27 so that the suction valve 24 is operated by the rocking motion of the lever 29 to control the supply of fuel in accordance with the relative position of the eccentric 27 and this as a projection of lever 29 influences the closing of the suction valve 24, the closing of this suction valve 24 can be varied by varying the position of lever 29. In other words the suction valve 24 can be closed later or earlier quite independently of the governor, so that more or less fuel can be supplied to the internal combustion engine without any preceding action of the engine governor. On one side of piston 34 acts the air pressure and on the other a spring 37. If the charging air pressure drops, the pressure on the piston drops also and piston 34 rises, shaft 29 is turned by means of levers 36, so that the suction valve 24 is closed later than previously and less fuel fed to the internal combustion engine. Piston 34 may also be provided with a handwheel 38 on the threaded piston rod 35 allowing for adjustment by hand. For instance with a right hand thread on rod 35, piston 34 can be pulled downwards by turning the handwheel 38 to the right. This arrangement allows to adjust the fuel pump for full admission, even when the full charging pressure in pipe 18 or above the piston 34 is not yet reached. If the handwheel 38 is turned to the left it moves away from the cover of cylinder 33 and piston 34 becomes free to take the equilibrium position. The lower end of the cylinder 33 is connected to the exhaust pipe 12 or one of the pressure stages of the exhaust gas turbine by means of pipe 19 or 19' respectively. Equilibrium of the forces on either side of piston 34 therefore takes place when spring force and force due to the exhaust gas pressure are equal to the forces due to the air pressure. The fuel admission to the internal combustion engine is made dependent on both the ratio of air and exhaust pressure. This arrangement has the big advantage, that at a sudden rise of the exhaust pressure without a corresponding rise in the air pressure the fuel admission to the internal combustion engine is reduced as the piston rises, so that the fuel admission to the internal combustion engine can be entirely stopped. On the other hand, when the charging pressure is high, piston 34 is forced downward and the fuel quantity fed to the internal combustion engine increases. Thus, with the arrangement shown in Figure 2 the maximum fuel supply to the internal combustion engine is limited by the charging air pressure in such a way, that the fuel quantity allowed to be pumped to the combustion cylinders cannot be exceeded. During normal performance of the engine the amount of fuel fed to the combustion cylinders is inside of the maximum allowable quantity. Up to this maximum quantity the governor of the engine can so influence the regulating linkage that any amount of fuel is delivered to the internal combustion engine. The maximum allowable quantity can never be exceeded, as the device according to the invention acts upon the

suction valve of the fuel pump as soon as this maximum amount is reached.

In Figure 3 a similar arrangement to that in Figure 2 is shown, also for limiting the maximum fuel supply. Piston 34 moves in a horizontal cylinder 33 and its movement is transmitted by rod 35 to the lever 39. If piston 34 moves to the right lever 39 turns anti-clockwise, thereby opening the suction valve so that the delivery of the fuel pump is partly or entirely interrupted. This occurs when the pressure in the charging pipe 18 falls below the admissible value or when the exhaust pressure in pipe 19 becomes too big. With handwheel 38 the pressure of spring 37 can be increased and piston 34 moved to the right, so that by means of crank lever 39 the suction valve 24 can be opened. An additional hand adjusting device 40, 41 is provided for, by means of which the fuel delivery can be varied independently of the arrangement 33, 34 and 35. An arrangement of this kind is particularly suitable for engines of vehicles. For the rest the arrangement is as in Figure 2.

The device according to the invention may also be applied to engines in which the fuel supply is regulated by hand, as e. g., in marine engines and railway engines. Such a constructional form is shown in Figure 4. Numerals 40, 41 represent the hand regulating device for the fuel pump 9. By moving lever 40 shaft 41 is turned whereby the fuel quantity pumped to the engine cylinders is affected. Lever 40 is keyed to shaft 41, but lever 44 is loose thereon. Lever 40 is provided with a nose 54 that strikes against a part of the lever 44 so that the movement of the lever 40 is limited by the lever 44, whereas the position of the lever 44 depends on the air and exhaust pressures. The shaft 41 is similar to shaft 30 and is in a similar manner provided with eccentricities. Lever 40 can be fixed in any position on segment 43. The means 33, 34, 35 and 37 are arranged to act in such a manner on a lever 44, as described that this lever prevents lever 40 from being turned to the right beyond a determined position. The lower the charging air pressure and the higher the exhaust pressure the more piston 34 is pushed over to the left thereby moving lever 44 also to the left. Lever 44 pushes lever 40 more to the left, corresponding to a position where less fuel is pumped to the combustion cylinders. When the charging pressure rises, a greater fuel supply is permissible, piston 34 moves to the right and also lever 44, being directly connected to piston 34. It is therefore possible to turn lever 40 more to the right and increase the fuel supply to the combustion cylinders. In an arrangement according to Figure 7 the fuel delivery is thus adjusted by hand but the maximum admissible fuel quantity is limited in dependency of the charging and exhaust pressure. To move piston 34 also at will handwheel 38 is provided for.

In Figure 2 the arrangement acts as safety device, in Figure 3 as cut-off device, but it may also be constructed so as to act as a safety device only. In this latter case the arrangement may be such, that when the charging pressure is low, it is impossible to supply more than a certain, allowable quantity of fuel to the combustion cylinders, whereby the allowable quantity increases with increasing charging air pressure. If the charging pressure drops the arrangement acts in such a way that the allowable fuel quantity is reduced.

What I claim is:

An internal combustion engine comprising in combination a combustion cylinder, a turbine, an air inlet duct and an exhaust gas duct delivering exhaust gas to said turbine, a charging blower driven by said turbine for delivering a compressed charge to said cylinder, a fuel pump for delivering fuel to said cylinder, an inlet valve having a stem to control the inlet of fuel to said pump, 5 a safety device including a fluid pressure respon-

sive member, ducts connecting said pressure responsive member to both of said air inlet and said exhaust gas ducts, an abutment member co-acting with the stem of the inlet valve for controlling its time of closure during the delivery 5 stroke of said fuel pump, an eccentric device supporting said abutment and means actuated by said pressure responsive means for rocking said eccentric.
